UNITED STATES PATENT OFFICE.

NATHAN W. CRANDALL, OF MERIDEN, CONNECTICUT, ASSIGNOR TO RUSSELL & ERWIN MANUFACTURING COMPANY, OF NEW BRITAIN, CONNECTICUT, A CORPORATION OF CONNECTICUT.

LOCK AND LATCH.

SPECIFICATION forming part of Letters Patent No. 752,205, dated February 16, 1904.

Application filed May 11, 1903. Serial No. 156,559. (No model.)

To all whom it may concern:

Be it known that I, NATHAN W. CRANDALL, a citizen of the United States, residing at Meriden, in the county of New Haven, State of Connecticut, have invented certain new and useful Improvements in Locks and Latches, of which the following is a full, clear, and exact description.

My invention relates to improvements in locks and latches; and the object is to improve and simplify the construction of the same.

In the drawings, Figure 1 is an elevation of a door-lock with the cover-plate removed. Fig. 2 is a similar view of a portion of the lock shown in Fig. 1, certain parts being removed and broken away. Fig. 3 is a section of a lock on the plane of line 3 3, Fig. 1, showing the cover-plate in place.

1 is a lock case or frame.

2 is a latch.

3 is a bolt.

The latch is controlled by the slide 4, operated by a roll-back 5.

The bolt 3 may be operated in the usual manner by a key, (not shown,) which may be inserted through a keyhole 6 in the case 1. The bolt 3 passes through an opening in the face-plate 7 of the lock-case and is guided partially thereby. The guide for the bolt 30 within the lock-case comprises what I term the "screw-stump" 8. This screw-stump may be located at any suitable point near the center of the lock case or frame 1 and is arranged to receive a suitable screw provided 35 to hold the cover 9 in place.

11 is a tumbler pivotally mounted on the screw-stump 8. The tumbler has a nose 12, which normally engages in a notch in the bolt 3, as best seen in Fig. 1. The tumbler normally stands into the path of the key by which the lock is operated. When the proper key is inserted, it will elevate the tumbler to the desired height to free the bolt and will also clear the edge of a notch or recess in the lower 45 side of the bolt, whereupon the operator may

by still further turning the key throw the bolt into the locking position.

The particular advantage of the foregoing construction resides in the simplicity of construction attained by guiding the bolt 3 on 50 the screw-stump 8 and of hinging the tumbler 11 on the same member. A spring 13 for operating the tumbler may also be supported on the screw-stump. A supplemental spring 14 may also be employed, the same being used to supplement the action of the latch-slide 4 in returning the roll-back hub to its normal position, the same being illustrated in Fig. 1. In Fig. 2 the tumbler 11 has been removed to show how the bolt is guided on 55 the same stud upon which the tumbler is pivotally mounted. In this figure it will be seen that the bolt has a slot in it to permit of the sliding movement thereof.

The assembling of the parts is very simple. 60 The various members are easily inserted, whereupon the cover 9 may be put in place and secured by means of a single screw.

What I claim is—

1. In a lock, a latch-slide, a latch-bolt in 70 connection therewith but having a retractive movement independently thereof, a separate locking-bolt, a tumbler therefor, a spring connecting said tumbler and said latch-slide, and a second spring connecting said tumbler 75 and said latch-bolt.

2. In a lock and latch mechanism, the combination of a locking-bolt, a tumbler therefor, a latch-bolt, a latch-slide therefor, a spiral spring having one end engaging said tumbler 80 and the other end engaging said bolt, and a second spring having one end engaging said tumbler and the other end engaging said slide.

Signed at New Britain, Connecticut, this 28th day of April, 1903.

NATHAN W. CRANDALL.
